UNITED STATES PATENT OFFICE.

WILLIAM MOLLER, OF NEW YORK, N. Y.

AMALGAMATOR.

SPECIFICATION forming part of Letters Patent No. 251,914, dated January 3, 1882.

Application filed July 16, 1881. (No model.)

To all whom it may concern:

Be it known that I, WILLIAM MOLLER, a citizen of the United States, residing at New York, in the county and State of New York, 5 have invented new and useful Improvements in Amalgamators, of which the following is a specification.

This invention relates to that class of amalgamators in which the mixed pulp and mercury are subjected to the triturating action of revolving mullers co-operating with a suitable bed, the mullers being connected to a vertical shaft in the center of the amalgamating-pan.

My invention consists in the combination, 15 with the amalgamating-pan, a vertical shaft, a bed surrounding the latter, and a series of gravitating mullers operated by the shaft, of an annular trough elevated above the plane of the bed on which the mullers travel and below the lateral discharge-orifice in the amalgamating-pan, whereby the heavy particles of metal which are set free are deposited in the elevated annular trough, while the finer or lighter particles of metal float off through the 25 discharge-orifice of the pan.

The amalgamating-pan is constructed with an outlet-orifice in its side and with a lateral branch or wing opposite to such orifice having traps (one or more) in the bottom thereof, and, 30 in the branch or wing of the pan are arranged cloth-covered rollers (one or more) dipping into the traps, so that the fine or floating metal adheres to the rollers, and if the traps are supplied with mercury the metal is thereby absorbed from the rollers, forming an amalgam.

This invention is illustrated in the accompanying drawings, in which Figure 1 represents a plan or top view. Fig. 2 is a vertical longitudinal section.

40 Similar letters indicate corresponding parts.

The letter A designates the amalgamating-pan; B, the vertical shaft; C, the bed; D, the mullers; E, the trough; F, the outlet-orifice of the pan; G, the branch or wing of the pan; H, 45 the traps, and I the rollers.

The pan A has the usual circular shape, and the shaft B extends through a pillar, J, in the center thereof, while the bed C surrounds the shaft, the bed being placed on the bottom of 50 the pan and having, like the pan, a circular outline. The mullers D are connected to the shaft B by radial arms K, projecting from a

hub, L, on the shaft, and they rest on the upper or grinding surface of the bed C by their inherent gravity.

The trough E has an annular shape and surrounds the bed C, while it is raised above the upper surface of the bed, as shown, the same being situated next to the side of the pan, and being preferably arranged above a heating-chamber, N, adapted to be supplied with steam or the like. From the bottom of the annular trough E extends a discharge-port, O, provided with a valve, P.

The outlet-orifice F is in the side of the pan 65 A above the annular trough E, and the branch or wing G of the pan projects laterally therefrom opposite to the outlet-orifice, while the traps H are formed in the bottom of the branch or wing, each being provided with a plug, Q. 70 The branch or wing G, moreover, is provided with an escape-pipe, R, and the outlet-orifice F with a gate, F'.

The rollers I are covered with cloth, and they extend parallel to the traps H directly above 75 them, their shafts being so arranged that the rollers dip into the traps—namely, with their cloth coverings. Said shafts of the rollers I have their bearings in the sides of the branch or wing G, and they are provided with pulleys 80 S, connected together by a belt, T, one of the shafts being, moreover, provided with a driving-pulley, U. If desired, the cloth coverings of the rollers I may be arranged in the form of flaps to increase the effective area of the rollers.

The ore to be amalgamated is fed to the pan in the form of a pulp, together with a suitable quantity of mercury, as near as possible to the center of the pan, and a revolving motion being imparted to the vertical shaft B, the mixture is subjected to the action of the mullers D, and the heavy particles of metal thereby set free are deposited in the annular trough E, while the fine or lighter metal floats off into the branch or wing G, where it is caught by the rollers I. The traps H are supplied with mercury, and a revolving motion being imparted to the rollers I, the metal adhering thereto is presented to the mercury and is absorbed thereby. In this manner the waste of metal is prevented to the greatest possible extent, and a maximum yield is obtained from a given quantity of ore.

The traps H and the cloth-covered rollers dipping therein can be used also independently of the pan—as, for example, the ore may be fed thereto from the zinc plates of a stamp-
5 mill, and in that event the traps may be suspended in a box, so that the sand readily separates from the lighter particles and collects on the bottom of the box.

What I claim as new, and desire to secure
10 by Letters Patent, is—

1. In an amalgamating apparatus, the combination, with the pan, the vertical shaft B, the bed surrounding the shaft, and the revolving gravitating mullers, of the annular trough E, elevated above the plane of the bed on which the mullers travel, and arranged adjacent to the sides or vertical walls of the pan below the lateral outlet-orifice in the latter, all substantially
15 as and for the purpose described.

2. The combination, substantially as herein-
before set forth, of the amalgamating pan con-
structed with the outlet-orifice in its side and
with the lateral branch or wing opposite to
such orifice, having traps (one or more) in the
bottom thereof, and the revolving cloth-cov-
ered rollers (one or more) arranged in said
branch of the pan to dip into the traps, for the
purpose specified.

In testimony whereof I have hereunto set
my hand and seal in the presence of two sub-
scribing witnesses.

WILLIAM MOLLER. [L. S.]
